(57) CLAIM

The ornamental design for a tea table, as shown and described.

DESCRIPTION

FIG. 1 is a top-front-right perspective view of a tea table showing my new design.

FIG. 2 is a bottom-front-right perspective view thereof.

FIG. 3 is a front view thereof.

FIG. 4 is a rear view thereof.

FIG. 5 is a right side view thereof, a left side view being a mirror image of the right side view.

FIG. 6 is a top view thereof; and,

FIG. 7 is a bottom view thereof.

1 Claim, 6 Drawing Sheets

FIG. 1

FIG. 2

FIG. 3

FIG. 4

FIG. 5

FIG. 6

FIG. 7
